UNITED STATES PATENT OFFICE.

THOMAS L. STURTEVANT, OF FRAMINGHAM, MASSACHUSETTS.

STEAM-BOILER.

SPECIFICATION forming part of Letters Patent No. 408,996, dated August 13, 1889.

Application filed April 22, 1889. Serial No. 308,098. (No model.)

To all whom it may concern:

Be it known that I, THOMAS L. STURTEVANT, a citizen of the United States, residing at Framingham, in the county of Middlesex 5 and State of Massachusetts, have invented certain new and useful Improvements in Steam-Boilers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to steam-boilers, particularly that class having a forced circulation, wherein water introduced continuously at one end of the tubular system escapes in the form of steam at the other and opposite 20 end of said system.

The object of this invention is to provide a large heating-surface; further, in connection therewith, to obviate the objection which would be caused by the use of the additional 25 tubular flues necessary to produce such heating-surface, I propose to flatten the same. By this arrangement and construction the interior space of the external shell or element is less obstructed, ample room is furnished for 30 the escape of smoke and gases, while at the same time an equal area or surface for heating the liquid still exists.

The drawings represent, in Figure 1, a vertical longitudinal sectional elevation of a 35 boiler containing my improvements. Fig. 2 is a transverse section on line $x-x$, looking toward the lamp end of the boiler. Fig. 3 is an end view of one of the unions.

In the drawings, the boiler, of a horizontal 40 type, as a complete organization is shown at $\mathbb{A}$, consisting of a main exterior shell or element B, which is a double-tube section composed of the tubes $a a'$, having their opposite adjacent ends closed by solid annular rings 45 $b b$, secured by transverse bolts or pins. In this way a tight joint is produced and a steam-generating chamber c, formed capillary in the present instance. One end of this element B is connected with a smoke-stack C, while at 50 the opposite end is located, preferably, a hydrocarbon-burner D, of any suitable descrip-

tion. The water-supply pipe is at E, and united with the element B at the end opposite the lamp, to permit the water to become gradually heated as it is forced toward the 55 lamp or heating agency.

Centrally of the bore of the shell B are grouped a number of small tubes $d d$, circular their entire length and terminating at the lamp end of the boiler in the union F, which 60 connects with the steam-discharge e, and at the chimney end of said boiler in the union G. Thus the central portion of the boiler is occupied while a space exists between the external shell or element B and the group of 65 pipes or tubes $d d$. To provide for a still greater heating-surface, and thereby make available all the interior space of the element B, I dispose about the central pipes $d d$ a series of tubes $f f$, which are flattened or made 70 oval for their entire length, with the exception of their extremities, which are circular to adapt them to engage with elbows connecting them with other parts of the system. By this means each pipe presents the same heating- 75 surface which it otherwise would were it circular in cross-section at all points, and the interior space of the boiler is not so crowded, while the smoke and gases of combustion are free to escape under a natural draft. Said 80 group of pipes terminates at the chimney end of the boiler within the union G, entering the latter, as shown in the drawings. The opposite ends are united with pipes $h h$, flattened in that portion of their length adjacent to said 85 group $f f$. These pipes h communicate by suitable fittings with the exterior shell or element B. Heat being applied at the lamp end and water being continually introduced by liquid-forcing apparatus through the pipe E, 90 the circulation is as follows: Through the generating-chamber c, in the double-tube section B, toward the lamp end of the boiler; thence, by way of tubes h , in the reverse direction, or toward the chimney end thereof, again 95 toward the lamp end, and return by way of the group of flattened or oval tubes $f f$ to the union G. From here the water, which is now in the form of steam, is transmitted through the circular flues $d d$, wherein it is superheated and dried, to the union F, whence it is 100 conveyed by the discharge-pipe e to the source

- to be supplied. The employment of these flattened tubes within the combustion-chamber or smoke-passages of a boiler suberves several important advantages—a freer passage for the products of combustion is secured and at the same time the surface of the metal tubes exposed to the fire or the water is not diminished. Further, the flattened tubes in a tubular boiler diminish the amount of water in the tubes without reducing the amount of tube-surface exposed to the water or fire. The narrower tubes will heat more quickly, and the water heating more rapidly will circulate more rapidly.
- I do not desire to claim, broadly, flattened tubes for steam-generating purposes, since I am aware that flattened tubes have been used in boilers.
- What I desire to claim is—
1. A boiler for steam-generating purposes composed of an exterior shell, a series of cylindrical tubes centrally of its bore, a group

of flattened tubes circular in cross-section at their extremities, and between said shell and the inner tubes the smoke-flue at one end and the heating agency at the opposite end of said boiler, with means for supplying water and discharging steam, substantially as and for purposes herein set forth.

2. In a steam-boiler, the double-tube element B, the central group of tubes d d, the unions F G, in which said tubes terminate, combined with the flattened tubes f f, circular at their extremities, and the tubes h h, by which the union G is united with the element B, the water-supply pipe E, steam-discharge e, and a suitable heating agent, substantially as specified.

In testimony whereof I affix my signature in presence of two witnesses.

THOMAS L. STURTEVANT.
